[57] CLAIM

The ornamental design for ice container housing for attachment to box fans for enhanced cooling, as shown.

DESCRIPTION

FIG. 1 is a perspective view of an ice container housing for attachment to box fans for enhanced cooling showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front end elevational view thereof; and,

FIG. 7 is a rear end elevational view thereof.
